PRESS FOR THE PRODUCTION OF ARTISTIC PRINTS AND IMPRESSIONS

Filed Sept. 21, 1927

Inventor:
Josef Grünberg
By B. Singer, Atty.

UNITED STATES PATENT OFFICE

JOSEF GRÜNBERG, OF BERLIN, GERMANY

PRESS FOR THE PRODUCTION OF ARTISTIC PRINTS AND IMPRESSIONS

Application filed September 21, 1927, Serial No. 221,065, and in Germany September 24, 1926.

My United States Patent 1,547,871 relates to a press for the production of artistic prints and impressions. The material to be printed etc., viz paper or the like, is subjected to pressure by means of an elastic wall of a pressure receptacle by which it is pressed onto the original block or matrix. It has, however, been discovered that it is connected with difficulties to pack and tighten the inserted elastic wall with respect to the atmosphere on account of the high pressure existing in said pressure receptacle. This is true, in fact, of all joints of the press, and to judge correctly upon the importance of the matter it must be considered that if only a trace of the liquid substance used, viz, preferably oil, escapes valuable prints may be rendered useless.

The object of the present invention is to do away with that grave drawback, and for this purpose I now make use of an elastic wall constituted by a plate consisting of a yielding material and having a flange which acts as packing and tightening means under the action of the pressure existing in the pressure receptacle. The flanged rim of the yielding plate is, preferably, so high that it extends from the bottom to the top of the pressure space and covers, therefore, all joints.

In my above-mentioned previous United States patent the abutment for the original block, viz the printing table, is formed in particular cases by an elastic wall of a pressure receptacle, and in order to hold that wall tightly upon its seat the rim of the same is subjected, during the printing procedure, to the pressure of the upper elastic wall, the rim portion of which, therefore, can no more act as pressing surface. This is obviously another drawback, but also this drawback is overcome in my present improved press. In this latter also the abutment is formed by a plate consisting of a yielding material and having a flanged packing or tightening rim. The packing and tightening procedure is effected directly by the flanged rim, and the elastic surface acting during the printing procedure needs no more to act as a means for packing and tightening the abutment surface.

When the flanged rim of the elastic print-

ing surface, or of abutment surface, extends from the bottom to the top of the pressure space and, therefore, covers the side walls of the same, porous places existing, perhaps, in the walls of the pressure receptacle are insignificant, as the pressing medium does not contact directly with said walls, and in order to prevent the liquid under pressure from contacting directly with the walls of the press the surfaces of the upper and the lower liquid space can be provided with a covering of a material impervious to the fluid or liquid under pressure, for instance rubber. This covering may be formed by a hood forming, together with the elastic wall of the upper or the lower liquid space, a closed pressure space.

The invention is illustrated diagrammatically and by way of example on the accompanying drawing on which is shown a vertical section through a printing press designed according to this invention.

On the drawing, 1 denotes the frame of the press and 2 an inserted cover, the lower part of which is concavo-convex and forms below it an open space 3. This space is closed from below by a hollow elastic body 4, the wall 4¹ of which is flanged at its upper edge, the flange 4² contacting with the rim of the bottom part of the cover 2, the upper part of which is firmly connected with the frame or body of the press by screws or bolts (not shown). The member 4 may consist of rubber or the like. When the liquid under pressure, for instance an oil, is introduced into the space 3 and the member 4 through a pipe 5, all parts of this member, except the centre part, are pressed against the neighbouring rigid walls, whereby perfect tightness is obtained.

In the lower part of frame 1, below the member 4, a car 7, forming the printing-table, is movable on rails 6. The car is hollow and forms a space 3¹ also enclosing an elastic member 8 closing the space of the car and forming a chamber. Also this member consists preferably of rubber, and its side wall 8¹ has a flange 8², the whole being practically an inverted member 4, 4¹, 4², except the thick centre portion of the member 4. If pressure

is produced in the chamber 3¹, the sides and the flange of the member 8 are pressed against the neighbouring rigid walls, just as with the member 4, whereby the member 8 is tightened. The upper, horizontal, flat part of the member 8 supports the original piece together with the material to be printed or to be impressed, viz paper, paste-board, metal foil or the like. By lifting the car 7, for instance in the manner described in my aforesaid patent specification, the material to be printed or to be impressed is moved towards the elastic wall 4. Now the fluid or liquid under pressure is pressed into the chamber 3, i. e. the space enclosed between the members 2 and 4, whereby the printing or impressing is effected.

The bottom surface of the cover 2 and the inner bottom surface of the printing table 7, are provided, in the example shown, with coverings 9 and 9¹ consisting of a material, for instance rubber, impervious to the fluid or liquid under pressure. The upper cap-shaped covering 9 and the lower basin-shaped covering 9¹ have each a flanged rim 9² and 9¹ respectively, and each is inserted loosely into the respective cavity where it is held in place by the flange 4², or 8² respectively. It is, however, also possible to connect the contacting flanges by vulcanization. In every case the members 4 and 9 in the upper part of the press and the members 8 and 9¹ in the lower part of the same form closed chambers. The covering 9 is preferably provided with tubular extensions 9², as shown, the object of which is obvious.

I claim:

1. A printing press of the kind described, comprising in combination, a pressure receptacle open at one side, an elastic wall loosely inserted in said receptacle and arranged to close the open side of said receptacle, said elastic wall having an inwardly bent rim, arranged to lie close to the inner walls of said pressure receptacle and adapted to tighten up said receptacle when the pressure is increased within the latter.

2. A printing press of the kind described, comprising in combination, a pressure receptacle open at one side, an elastic wall loosely inserted in said receptacle and arranged to close the open side of said receptacle, said elastic wall having an inwardly bent rim and extending from the bottom of said pressure receptacle to the top of the same, said rim being arranged to lie close to the inner rigid walls of said pressure receptacle and adapted to tighten up said receptacle when under pressure.

60 3. A printing press of the kind described, comprising in combination, a pressure receptacle open at one side, an elastic wall loosely inserted in said receptacle and arranged to close the open side of said receptacle, said elastic wall having an inwardly bent rim and

extending from the bottom of said pressure receptacle to the top of the same, said rim being arranged to lie close to the inner rigid walls of said pressure receptacle and adapted to tighten up said receptacle when under pressure, and coverings on those portions of the rigid walls of said pressure receptacle which are surrounded by the rims of said elastic wall.

In testimony whereof I have affixed my signature.

JOSEF GRÜNBERG.
